UNITED STATES PATENT OFFICE.

BENHARD YOCH, OF ST. LOUIS, MISSOURI.

STEAM-ENGINE FOR MINING PURPOSES.

SPECIFICATION forming part of Letters Patent No. 286,105, dated October 2, 1883.

Application filed April 9, 1883. (No model.)

To all whom it may concern:

Be it known that I, BENHARD YOCH, of the city of St. Louis, in the State of Missouri, have invented a certain new and useful Improvement 5 in Steam-Engines for Mining Purposes, of which the following is a full, clear, and exact description, reference being had to the accompanying drawings, forming part of this specification, and in which—

- 10 Figure 1 is a side elevation of my improved mining-machine. Fig. 2 is a horizontal section on the line 2 2, Fig. 1. Fig. 3 is a detail vertical longitudinal section. Fig. 4 is a detail vertical transverse section.
15 My invention relates to a receiver placed upon the machine, into which the air or steam is discharged before entering the machine, as more fully described hereinafter.

My invention consists in points of novelty 20 pointed out in the claims.

Referring to the drawings, A represents the frame of the machine, and B the supporting-wheels.

Q represents the main cylinder of the machine, and Q' its valve-chest.

R represents the cylinder of the main-valve motor, and R' its chest.

S represents a receiver placed upon the machine, and communicating with the chest Q' 30 by means of a port, T, (see Fig. 4,) and with the chest R' through means of a port, U. (See Fig. 3.) These ports are provided with plug-valves T' U', respectively (See Figs. 3 and 4.) The valves are secured in bushings V W, 35 preferably, which are screwed into the sides of the receiver, as shown. The valves taper outward, the openings in the bushings being correspondingly tapering, so that the pressure on the inside tends to keep them tight. They 40 have operating-levers T' U'. (See Figs. 3 and 4.) The valves are located some distance from the bottom of the receiver, so that dirt and any

condensed steam there may be discharged into the receiver can settle in the bottom of the receiver, and not be carried into the working 45 parts of the machine, as is the case where the supply-pipe communicates directly with the chests. Dirt gets into the supply-pipe, when it is disconnected from the machine, in moving the machine from place to place, and then 50 when the pipe is connected to the machine again and the air turned on the dirt is blown into the machine, in my case into the receiver.

X represents a nipple for connecting the supply-pipe with the receiver.

Y represents a blow-off cock near the bottom of the receiver, for the discharge of dirt and water.

I claim as my invention—

1. In a mining steam-engine, a receiver 60 placed upon the machine for the purpose mentioned, and communicating with the valve-chests by means of suitable ports connected to the receiver above its bottom, substantially as described.

2. In a mining steam-engine, a receiver placed upon the machine for the purpose mentioned, and communicating with the chests by means of suitable ports provided with tapering plug-valves, through which the ports pass, 70 substantially as shown and described, for the purpose set forth.

3. In a mining steam-engine, the combination of main chest Q', small chest R', and receiver S, with which the supply-pipe or hose 75 connects, having ports T U communicating with the said chests, and provided with plug-valves T' U', tapering outward, so that the pressure in the receiver will tend to keep them tight, as set forth.

BENHARD YOCH.

In presence of—

SAML. KNIGHT,
GEO. H. KNIGHT.
